(57) **CLAIM**

We claim the ornamental design for an electronic switch, as
shown and described.

DESCRIPTION

FIG. 1 is a top perspective view of our new design comprising an electronic switch;

FIG. 2 is a bottom perspective view of the electronic switch of FIG. 1;

FIG. 3 is a right side view of the electronic switch of FIG. 1;

FIG. 4 is a left side view of the electronic switch of FIG. 1;

FIG. 5 is a front side view of the electronic switch of FIG. 1;

FIG. 6 is a rear side view of the electronic switch of FIG. 1;

FIG. 7 is a top view of the electronic switch of FIG. 1;

FIG. 8 is a bottom view of the electronic switch of FIG. 1;

FIG. 9 is a top perspective view of a second embodiment for the new design comprising an electronic switch;

FIG. 10 is a bottom perspective view of the electronic switch of FIG. 9;

FIG. 11 is a right side view of the electronic switch of FIG. 9;

FIG. 12 is a left side view of the electronic switch of FIG. 9;

FIG. 13 is a front side view of the electronic switch of FIG. 9;

FIG. 14 is a rear side view of the electronic switch of FIG. 9;

FIG. 15 is a top view of the electronic switch of FIG. 9; and,
FIG. 16 is a bottom view of the electronic switch of FIG. 9.
The broken lines and unshaded surfaces shown in the
drawings illustrate portions of the device that form no part
of the claimed design.
